Fig. 1.

Fig. 2.

A detailed line drawing of a glass bottle. The bottle has a narrow neck with a small circular label featuring a stylized 'Z' or 'B' shape. The main body of the bottle is wider and tapers slightly towards the base. The drawing uses fine lines and cross-hatching to create a sense of depth and texture.

UNITED STATES PATENT OFFICE.

FOREST H. MIRACLE, OF TULSA, OKLAHOMA, ASSIGNOR TO LLOYD G. OWEN, OF TULSA, OKLAHOMA.

SWAB.

Application filed April 30, 1927. Serial No. 187,939.

This invention relates to oil well swabs. An important object of the invention is to provide a novel form of swab employing a rubber or similar packing member which is adapted to contact with the oil well casing upon upward movement of the device and to contract to permit it to move freely in the casing when the device is moved downwardly whereby an efficient elevation of the liquid is accomplished when the device is elevated and wherein wear is eliminated or minimized when the device is moved downwardly.

A further object is to provide novel means for utilizing the pressure of the column of liquid above the device for expanding the packing member or members when the device is elevated.

A further object is to provide a novel form of packing which is adapted to be subjected to internal pressure upon upward movement of the device and wherein the upper end of the packing is anchored to prevent it from pulling downwardly upon the introduction of pressure, thus greatly increasing the efficiency of the device and lengthening the life of the packing.

A further object is to provide one or more packing devices carried by the usual hollow stem, each packing device having an internal chamber communicating through suitable openings with the stem, the latter having openings in its upper end to permit oil to flow downwardly into the pressure chambers to expand the packing members, the lower end of the stem having a check valve mounted thereon to permit the flow of fluid into the lower end of the stem when the device is lowered, the check valve being adapted to close upon upward movement of the stem.

Other objects and advantages of the invention will become apparent during the course of the following description.

In the drawings I have shown one embodiment of the invention. In this showing, Figure 1 is a central vertical sectional view,

Figure 2 is a detail section on line 2—2 of Figure 1, and,

Figure 3 is a detail perspective view of one of the packing members.

Referring to the drawings, the numeral 10 designates the usual tubular stem which is threaded or otherwise secured at its upper end to a head 11, the latter element having a threaded upper end 12 adapted for con-

nexion with a suitable tool to permit the device to be reciprocated. The head may be provided with a square or similar portion 13 adapted to be engaged by a wrench, as will be apparent. The upper end of the stem 10 is provided with radial openings 14 communicating with the interior of the well casing and with openings 15 formed in the head 11. The lower end of the stem is provided with a valve housing 16 in which is mounted a check valve 17 of ordinary construction.

The device forming the subject matter of the present invention comprises a rubber or similar packing member 18 which is shaped as shown in Figures 1 and 3. Any desired number of the packing members may be employed and in the present instance I have shown two of these devices mounted upon the stem. The upper end of the packing member extends into a retaining ring 19 which has an annular recess 20 in which the upper end of the packing member is arranged. The upper extremity of the recess 20 is enlarged as at 21 to receive the enlarged annular portion 22 of the packing member. The retaining ring 19 seats against the lower end of the head 11, as clearly shown in Figure 1. A lower retaining ring 23 is also employed, this ring being provided with a recess 24 receiving the lower end of the packing member. A nut 25 is threaded on the stem 10 and supports the lower end of the ring 23. It will be obvious that the adjacent ends of the rings 19 and 23 are spaced a substantial distance to permit the packing member 18 to project outwardly to contact with the oil well casing. The packing member is provided with an internal pressure chamber 26 which is arranged slightly above the center of the length of the packing member, and this chamber communicates with the interior of the stem 10 through radial openings 27. As stated, any number of the packing devices may be employed, the ring 19 of the uppermost device seating against the head 11. A nut 28 is threaded on the stem 10 and seats against the ring 19 of any other packing devices employed on the stem. In other respects, the packing devices are identical.

The operation of the device is as follows:

The nuts 25 are preferably adjusted in such position that the diameters of the packing members 18 are slightly smaller than 110

the internal diameter of the well casing whereby the device readily may be inserted in the well casing. The stem is adapted to be reciprocated by any suitable tool connected to the head 11, and upon downward movement of the device it will be apparent that oil may flow upwardly through the valve 17 and outwardly through the openings 14 and 15. Thus no pressure is created 5 within the chambers 26, and the packing members 18 remain at their normal size and move freely within the well casing. Upon 10 upward movement of the stem it will be apparent that the valve 17 closes, and oil from the column above the device flows into the stem through the openings 14 and 15, and into the chambers 26 through the openings 27. Owing to the weight of the column of 15 oil in the casing above the device, each of the packing members is subjected to substantial internal pressure when the device is moved upwardly, and this pressure expands 20 the packing members causing them to seat tightly against the well casing. The arrangement of the chambers 26 is such that an even pressure is exerted outwardly to cause the proper seating of the packing members against the well casing, it being understood that there is not only an outward pressure exerted by the column of oil, but also a slight downward pressure due to the upward movement of the device against the weight of the column of oil. It is for 25 this reason that the chambers 26 are arranged slightly above the centers of the packing members.

With devices of this character it has been found extremely difficult to prevent the downward slipping of the upper ends of the 40 packing members when pressure is introduced therein. With the present construction, however, it has been found that the bead or enlarged portion 22 of each packing member, seating within its corresponding recess portion 21, causes the upper end of the packing members to be retained in proper position, and in actual practice it has been found that a materially increased 45 efficiency is obtained and that the packing members last considerably longer in operation.

From the foregoing it will be apparent

that free downward movement of the device is permitted with little or no wear on the packing members taking place, and from 55 this fact it will be apparent that the packing members are adapted to last longer than other similar devices. When the stem 10 is moved upwardly, the packing members seat tightly against the well casing, thus elevating 60 an increased quantity of oil and at the same time creating a partial vacuum in the casing beneath the device, and the latter action transmits a suction to the producing rock thereby increasing production. 65

It is to be understood that the form of the invention herewith shown and described is to be taken as a preferred example of the same and that various changes in the shape, size and arrangement of parts may be resorted to without departing from the spirit of the invention or the scope of the subjoined claims. 70

I claim:

1. A swab comprising upper and lower 75 rings having recesses in their adjacent ends and adapted to surround a stem, the recess in said upper ring being enlarged at its upper end, an expansible packing member arranged between said rings, the upper end of 80 said packing member having an enlarged portion fitting within the enlarged portion of said last named recess, said packing member being provided with an internal pressure chamber, the stem being provided with an opening communicating with said chamber. 85

2. A swab comprising upper and lower rings having recesses at their adjacent ends and adapted to surround a stem, the recess 90 in said upper ring being enlarged at its upper end, and an expansible packing member arranged between said rings, the upper end of said packing member having an enlarged portion fitting within the enlarged portion 95 of said last named recess, said packing member being provided with an internal pressure chamber arranged slightly above the center of the distance between said rings, the stem being provided with an 100 opening communicating with said chamber.

In testimony whereof I affix my signature.

FOREST H. MIRACLE.
